THREE-ELEMENT FEEDWATER CONTROL

Igor J. Karassik, Maplewood, N.J.

Application July 1, 1957, Serial No. 669,137

6 Claims. (Cl. 122—451)

This invention relates to means providing automatic protection against damage to a boiler feed pump.

More particularly the invention contemplates the control of the delivery of feedwater from the boiler feed pump in such a manner as to substantially preclude the possibility of reducing the available net positive suction head at the suction of the boiler feed pump taking its suction from a direct contact heater supplied with steam from a bleed stage of the main turbine.

Boiler feedwater systems usually include the standard three-element control for regulating the flow of feedwater to the boiler. This three-element control includes a steam flow meter, a feedwater flow meter, and the usual boiler water level measuring device.

Steam flow from the boiler drum to the turbine and water flow from the pump to the boiler drum are accurately measured by the steam flow meter and feedwater flow meter respectively. These meters are generally balanced against each other by equating means such as a ratio relay or a differential control linkage so that the quantity of feedwater supplied to the drum is nearly equal to the quantity of steam output therefrom.

Should the balance be disturbed, as for example, by an increase in steam demand, the differential control linkage or the ratio relay will signal either a feedwater control valve or a control means for varying the speed of the pump to provide the necessary increased fluid flow to the boiler.

While the majority of large boiler feedwater installations are provided with three-element feedwater controls, there are variations as to the manner in which these controls are adjusted. In general, the feedwater input is regulated to closely parallel steam output, but the three-element control is sometimes adjusted to vary the boiler water level with the load as a precaution against the effects of swell and shrinkage. The water level measuring device operates, in the foregoing installation, to superimpose its influence upon the signal from the differential control linkage or ratio relay to actuate, usually, a feedwater control valve to make the necessary readjustments in rate of feedwater flow to the water drum.

Under conditions met in actual service, it has been noted that the foregoing control does not provide the desired feedwater flow rate regulation during a large or sudden drop in the main turbine load.

Specifically, the various effects taking place on a sudden or large reduction in turbine load are as follows: The turbine governor reduces steam flow in order to maintain the proper relation to the generated power; this reduction results in a proportionate pressure reduction in all of the successive stages of the turbine, including the bleed stage supplying steam to the direct contact heater.

The extraction line to the direct contact heater is usually provided with a check valve. The heater, being a reservoir of hot water, cannot reduce pressure as rapidly as the turbine bleed stage; therefore, the valve closes, isolating the heater from the turbine until the pressure

2

has dropped to that of the bleed point for the new turbine load. As a consequence, the net positive suction head available for the boiler feed pump, due to the changing relationship between the decaying heater pressure and the feedwater temperature at the suction of the pump, is seriously reduced.

Specifically, the foregoing reduction in available net positive suction head occurs because of a decrease in the margin between the suction pressure and the vapor pressure corresponding to the fluid temperature at the pump suction when the main turbine load is reduced rapidly. The heater pressure, which is a component of the suction pressure, drops during such a reduction without a corresponding immediate feedwater temperature reduction at the pump suction, thereby creating flashing in the suction components of the boiler feed pump which in effect reduces the available net positive suction head.

Obviously the foregoing reduction of the net positive suction head may have adverse effects on the component parts of a boiler feed pump and it is apparent that serious damage may result to the pump if there is an increase in the required flow to the boiler under these conditions.

Concomitant with the reduction in available net positive suction head there occurs, due to the reduction in steam flow from the boiler water drum, an increase in the pressure in the boiler water drum. This increase in pressure causes the bubbles in the drum to collapse and therefore indicate an apparent drop in the level of the water therein to the water level measuring device.

Accordingly, the water level measuring device signals for an increase in flow to the water drum, which increase in flow has a detrimental effect on the boiler feed pump because of the lack of sufficient net positive suction head resulting from the isolation of the direct contact heater as a consequence of the drop in the main turbine load.

Inasmuch as the capacity of a boiler feed pump operating in a power plant system is solely governed by the three-element control which is in turn regulated by the fluctuations in the main turbine load and the resulting rise or fall of the boiler level, some specific means must be applied to nullify the signal from the water level measuring device during a period of large or sudden load drop in the turbine.

This is accomplished in the present invention by a three-element control including a pneumatic means to transmit the impulses from the steam flow meter, a feedwater flow meter, and a level controller to the flow rate controlling mechanism; the direct contact heater being further provided with adjustable measuring means to nullify the signal from the level control to the flow rate control.

Accordingly, it is an object of this invention to provide a direct contact heater with means to nullify the signal from a water level measuring device when the pressure in the direct contact heater is decreasing at a rate in excess of a predetermined value.

While the invention will be described and shown in connection with a pneumatic system for transmitting the signals from the foregoing controls to the flow rate control means, it is not intended to so limit the invention, which may be applied advantageously to hydraulically operated control systems or electronic control systems or the various features of construction and combination of parts which will become apparent from the detailed description in connection with the accompanying drawings.

Figure 1 shows the measuring means for nullifying the signal of the water level measurer in a boiler feedwater installation having a control valve for varying the flow from the boiler feed pump.

Figure 2 shows the measuring means for nullifying the signal of the water level measurer in a boiler feedwater installation wherein water flow is controlled there-

through by adjusting the speed of the prime mover of a boiler feed pump.

Referring to the drawings, Figure 1 shows a typical open cycle boiler feedwater installation which generally includes: a direct contact heater 1, a boiler feed pump 2, a boiler water drum 3, a main turbine (not shown), and the usual feedwater regulation controls to be herein-after more fully described.

The direct contact heater 1 receives water through condensate line 4, which line communicates at the other end with a condensate pump, not shown, in the drawings. The water contained in the direct contact heater 1 being heated, and as a consequence pressurized, by steam supplied thereto through bleed line 5; which line communicates at the other end with a bleed stage of the main turbine.

The boiler feed pump 2 draws conditioned water from the direct contact heater 1 and transmits the water through discharge line 6 to the boiler water drum 3 of the feedwater installation.

The boiler water drum 3 is adapted to accommodate water in the lower portion 7 and steam in the upper portion 8. The steam being highly pressurized flows through steam line 9 to the main turbine for operation thereof.

Automatic feedwater flow regulation controls are customarily provided for feedwater installations to meet the exacting requirements of present day boilers.

The feedwater regulator controls comprise: a feedwater flow meter 10 for measuring the flow rate through discharge line 6, a steam flow meter 11 for measuring the flow through steam line 9, a water level measurer 12 for measuring the level in water drum 3, a check or non-return valve 13 in bleed line 5 for precluding the return from direct contact heater 1 to the main turbine, measuring means 14, such as an adjustable pressure rate relay, connected to the direct contact heater 1 for measuring the pressure therein and for nullifying the impulse of the water level recorder 12, which impulse is transmitted to a flow controlling device 15, such as a feedwater regulating valve, when the pressure in the direct contact heater 1 is decreasing in excess of a predetermined rate, and the usual impulse transmitting means generally designated 16 as for example, a pneumatic system for transmitting impulses from the foregoing measuring controls to the flow controlling device 15 to provide proper flow in the feedwater installation under most all conditions.

The feedwater flow meter 10 available on the open market is connected to either side of an orifice 17 disposed in discharge line 6 by pressure lines 18 and 19. Similarly, the steam flow meter 11 is connected to either side of orifice 20, disposed in steam line 9, by pressure lines 21 and 22.

Flow meter 10 and steam flow meter 11 are connected to one another as, for example, by a differential control linkage 23 so that the feedwater flow closely parallels the steam flow. Should the flow in steam line 9 deviate from the predetermined ratio, the differential linkage will actuate the flow controlling device 15, through impulse transmitting means 16, to increase or decrease the flow rate in discharge line 6 to maintain the system in equilibrium or at the predetermined ratio.

In addition, to insure the proper water drum level, a water level measurer 12 is provided for the water drum 3 and connected thereto through lines 24 and 25. An improper level impulse being transmitted through a junction box 26, such as a ratio relay and impulse transmitting means 16 to the flow controlling device 15 to make the proper readjustments in water level.

The usual impulse transmitting means 16 in a boiler feedwater installation comprises a pneumatic system provided with an air supply 27, pilot valves 28, an air operated control relay 29 sold under the trademark "Standatrol," and a selection box 30 permitting manual or automatic flow control of the feedwater.

Operation

In operation, an increase or decrease in steam flow through steam line 9 will vary the airloading pressure in pilot valve 28a above or below the neutral set, through differential control linkage 23. The variation is a result of a change in load demand; accordingly, an impulse is transmitted through "Standatrol" 29 and selection box 30 to flow control device 15 so that the flow is adjusted in feedwater line 6 to restore the predetermined balance between the flow meters 11 and 12.

The water level recorder 12 will actuate the flow controlling device 15 through junction box 26, "Standatrol" 29 and selector box 30 to adjust the flow to insure the proper water drum level in boiler water drum 3.

The adjustable measuring means 14, for example, a pressure rate relay, is connected to the direct contact heater 1 through line 31 for recording the pressure therein. An impulse being transmitted through pilot valve 28b, and line 32 to junction box 26 to nullify the signal from the water level recorder 12 when the pressure in the direct contact heater 1 is decreasing in excess of a predetermined value.

25

Modified form

Figure 2 of the drawings shows a modified form of the improved three-element control. Those parts having generally the same construction and purpose as the corresponding parts in Figure 1 have been given the same reference characters.

Instead of having a feedwater regulating valve 15 for metering the flow to the boiler, Figure 2 provides a repositioning means 15a such as a servomotor to control the throttling of the turbine 29 driving the boiler feed pump 2, and instead of the differential control linkage 23 for signaling for an increase or decrease in flow, Figure 2 provides a ratio relay 23a for maintaining the predetermined balance between the feedwater flow meter and the steam flow meter.

It will be understood that the invention is not to be limited to the specific construction or arrangement of parts shown, but that they may be widely modified within the invention defined by the claims.

What is claimed is:

1. Control means for a boiler feed system including a boiler for supplying power medium, a boiler feed pump for flowing fluid medium to said boiler, a direct contact heater for supplying fluid to said boiler feed pump, said control means comprising measuring means for measuring the flow of the power medium from the boiler, second flow measuring means between the boiler feed pump and the boiler, balancing means operatively connected to said first and second measuring means, flow controlling means in said system operatively connected to said balancing means and adapted to vary the flow of said boiler feed pump to said boiler, a water level measurer for said boiler operatively connected to said flow control means whereby said water level measurer will signal said flow control means to increase or decrease the flow to said boiler to hold the fluid medium therein between predetermined limits, and pressure measuring means connected to said direct contact heater and operatively connected to said water level measurer to nullify the signal transmitted from said water level measurer to said flow control means when the pressure in said direct contact heater is being reduced at more than a predetermined rate.

2. Control means for a boiler feed system including a boiler for supplying power medium, a boiler feed pump for flowing fluid medium to said boiler, a direct contact heater for supplying fluid to said boiler feed pump, said control means comprising measuring means for measuring the flow of the power medium from the boiler, second flow measuring means between the boiler feed pump and the boiler, balancing means operatively connected to said first and second measuring means, flow

75

Controlling means in said system adapted to vary the flow of said boiler feed pump to said boiler, impulse transmitting means operatively connected to said balancing means and said flow controlling means whereby a signal from said balancing means will be transmitted through said impulse transmitting means to said flow controlling means, a water level measurer for said boiler operatively connected to said impulse transmitting means whereby said water level measurer will signal said flow control means to increase or decrease the flow to said boiler to hold the fluid medium therein between predetermined limits, and pressure measuring means connected to said direct contact heater and operatively connected to said water level measurer to nullify the signal transmitted from said water level measurer to said flow control means when the pressure in said direct contact heater is being reduced at more than a predetermined rate.

3. Control means for a boiler feed system including a boiler for supplying power medium, a boiler feed pump for flowing fluid medium to said boiler, a direct contact heater for supplying fluid to said boiler feed pump, said control means comprising measuring means for measuring the flow of the power medium from the boiler, second flow measuring means between the boiler feed pump and the boiler, balancing means operatively connected to said first and second measuring means, flow controlling means in said system adapted to vary the flow of said boiler feed pump to said boiler, impulse transmitting means operatively connected to said balancing means and said flow controlling means whereby a signal from said balancing means will be transmitted through said impulse transmitting means to said flow controlling means, a water level measurer for said boiler operatively connected to said impulse transmitting means whereby said water level measurer will signal said flow control means to increase or decrease the flow to said boiler to hold the fluid medium therein between predetermined limits, and an adjustable pressure rate relay connected to said direct contact heater and operatively connected to said water level measurer to nullify the signal transmitted from said water level measurer to said flow control means when the pressure in said direct contact heater is being reduced at more than a predetermined rate.

4. Control means for a boiler feed system including a boiler for supplying power medium, a boiler feed pump for flowing fluid medium to said boiler, a direct contact heater for supplying fluid to said boiler feed pump, said control means comprising measuring means for measuring the flow of the power medium from the boiler, second flow measuring means between the boiler feed pump and the boiler, balancing means operatively connected to said first and second measuring means, flow controlling means in said system operatively connected to said balancing means and adapted to vary the flow of said boiler feed pump to said boiler, a junction box operatively connected to said flow controlling means, a water level measurer for said boiler operatively connected to said junction box whereby said water level measurer will signal said flow control means through said junction box to increase or decrease the flow to said boiler to hold the fluid medium therein between predetermined limits, and an adjustable pressure rate relay connected to said direct contact heater and operatively

connected to said junction box to nullify the signal transmitted from said water level measurer to said flow control means when the pressure in said direct contact heater is being reduced at more than a predetermined rate.

5. Control means for a boiler feed system including a boiler for supplying power medium, a boiler feed pump for flowing fluid medium to said boiler, a direct contact heater for supplying fluid to said boiler feed pump, said control means comprising measuring means for measuring the flow of the power medium from the boiler, second flow measuring means between the boiler feed pump and the boiler, balancing means operatively connected to said first and second measuring means, flow controlling means in said system adapted to vary the flow of said boiler feed pump to said boiler, impulse transmitting means operatively connected to said balancing means and said flow controlling means whereby a signal from said balancing means will be transmitted through said impulse transmitting means to said flow controlling means, a ratio relay operatively connected to said flow controlling means, a water level measurer for said boiler operatively connected to said ratio relay whereby said water level measurer will signal said flow control means to increase or decrease the flow to said boiler to hold the fluid medium therein between predetermined limits, and pressure measuring means for said direct contact heater and operatively connected to said ratio relay to nullify the signal transmitted from said water level measurer to said flow control means when the pressure in said direct contact heater is being reduced at more than a predetermined rate.
6. Control means for a boiler feed system including a boiler for supplying power medium, a boiler feed pump for flowing fluid medium to said boiler, a direct contact heater for supplying fluid to said boiler feed pump, said control means comprising measuring means for measuring the flow of the power medium from the boiler, second flow measuring means between the boiler feed pump and the boiler, balancing means operatively connected to said first and second measuring means, flow controlling means in said system adapted to vary the flow of said boiler feed pump to said boiler, impulse transmitting means operatively connected to said balancing means and said flow controlling means whereby a signal from said balancing means will be transmitted through said impulse transmitting means to said flow controlling means, a ratio relay operatively connected to said flow control means, a water level measurer for said boiler operatively connected to said ratio relay whereby said water level measurer will signal said flow control means to increase or decrease the flow to said boiler to hold the fluid medium therein between predetermined limits, and an adjustable pressure rate relay connected to said direct contact heater and operatively connected to said ratio relay to nullify the signal transmitted from said water level measurer to said flow control means when the pressure in said direct contact heater is being reduced at more than a predetermined rate.
